RETRACTABLE COUPLER FOR LOCOMOTIVE STRUCTURES

James C. Travilla, Jr., Swarthmore, Pa., and William C. Krautheim, Normandy, Mo., as signors to General Steel Castings Corporation, Granite City, Ill., a corporation of Delaware

Application December 22, 1944, Serial No. 569,374

14 Claims. (Cl. 213—4)

1

The invention relates to locomotive pilot and coupler structure of the type in which the coupler swings from functioning position into a pocket in the pilot and the pocket opening may then be closed by a plate forming a continuation of the front wall of the pilot. Structure of this general type is shown in J. G. Bower Patent No. 2,104,846, issued January 11, 1938.

The main object of the present invention is to provide a construction which will better resist buffing and draft forces applied to the coupler, and particularly to reduce or eliminate bending moments on the pivot pin about which the coupler shank swings.

This and other detail objects as will appear from the following description are attained by the structure illustrated in the accompanying drawings, in which—

Figure 1 is a top view of a locomotive pilot beam and pilot, a portion of the structure being sectioned horizontally to better illustrate the parts, the coupler being shown in functioning position.

Figure 2 is a front elevation of the structure shown in Figure 1, the pocket closure plate being shown in functioning position.

Figure 3 is a side elevation looking towards the left hand end of the pilot and pilot beam as shown in Figure 2.

Figure 4 is a longitudinal vertical section taken on the line 4—4 of Figure 1.

The pilot beam 1 is shown attached to the front end of the locomotive main frame 2 and mounting the rear wall 3 of the locomotive pilot. The pilot front walls 4 converge forwardly of the locomotive and merge with each other and with the pilot end walls 5. The pilot walls are apertured at 6 in the usual manner and the pilot includes a forwardly opening pocket P having a top wall 7, a bottom wall 8 (Figure 4) and side walls 9 (Figure 1). Top wall 7 has a depending boss 10. Bottom wall 8 has an annular raised shelf 11 and an upstanding boss 12 disposed centrally of the shelf.

The coupler carried by the pilot includes a head 13 and an integral shank 14 the rear end of which has cylindrical-shaped portions 15 projecting upwardly and downwardly from the body of the shank. The rear end of the shank is apertured to receive the pivot pin 16 which is seated in bearings provided therefor in bosses 10 and 12. The coupler swings horizontally on pin 16 from the functioning positions shown in Figures 1 and 4 to a retracted non-functioning position shown at 13a in Figure 1. The coupler shank 14 rests upon the upper face of boss 12 and extends sub-

stantially the full distance between the opposing faces of bosses 10 and 12.

An arcuate plate 18 is shaped to close the pocket opening in the pilot front walls 4 and is supported through an integral horizontal flange 19 (Figure 4) resting on shelf 11 and apertured to surround boss 12. Another flange 20 surrounds the lower cylindrical-shaped terminal portion 15 of the coupler shank so that the closure plate may pivot thereon as it is swung about the axis of pin 16 from the pocket closing position shown in Figures 2 and 3 to the retracted position as shown in Figures 1 and 4.

The closure plate has an upper flange 21 cooperating with flanges 19 and 20 in reenforcing the closure plate, and an upright web 22 extends between flanges 20 and 21 and is substantially V-shaped in horizontal contour (Figure 1). The sides of the V are disposed to engage the sides of the coupler shank and move the coupler from retracted position to projected position, or vice versa, as plate 18 is swung manually from its pocket closing position to its retracted position, or vice versa. A locking lever 23 (Figure 2) pivoted on plate 18 operates a vertically sliding bolt 24 receivable in suitable apertures A in bottom wall 8 to retain plate 18 in selected position. When plate 18 is retracted, as shown in Figures 1 and 4, the angle between the inclined portions of web 22 accommodates the normal swinging of the coupler on curved track between the extremes indicated at 13 and 13a in Figure 1. The coupler head is supported from flange (Figure 4) 19 by a wear plate 25 on the flange.

The structure provides for the direct support of the rear end of coupler 13, 14 by boss 12 and pin 16 and since the portion of the coupler receiving the pin extends substantially the full distance between bosses 10 and 12, bending moments on the pin are substantially eliminated, thus insuring greater strength of the pin for a given diameter and providing maximum depth of the pin-receiving portion of the coupler shank for a given depth of the pocket. The closure plate is supported at widely spaced points by shelf 11 and independently of the coupler supporting boss 12. The separate bearing of the coupler and the closure plate on the pocket parts simplifies the construction and avoids the fitting of the coupler and closure plate to each other and avoids the use of shims between these parts as have been used previously for this purpose.

The details of the structure may be varied substantially without departing from the spirit of the invention, and the exclusive use of those mod-

ifications coming within the scope of the claims is contemplated.

What is claimed is:

1. In combination, a locomotive pilot having a forwardly opening coupler-receiving pocket provided with a bottom wall, a plate movable to close said opening and having a part resting on said bottom wall to support the plate, and a coupler movable into and out of said pocket to non-functioning and functioning positions and having a part resting directly on said wall, independently of said plate part, to support the coupler.

2. In combination, a locomotive pilot having a forwardly opening pocket with a bottom wall, a coupler including a shank with its rear end portion forming a bearing resting on said bottom wall, a pivot pin extending through said shank portion and said bottom wall, the coupler being movable about the axis of said pin to be projected from said pocket or to be retracted within it, and a plate movable about said pin axis to close or to expose the pocket opening and provided with a horizontal flange resting on a portion of said bottom wall spaced radially of said pin from said shank bearing.

3. In a locomotive pilot provided with a swinging coupler, a coupler-receiving pocket opening forwardly of the pilot and having vertically spaced upper and lower walls, an upright pivot pin having bearings in said walls, the coupler having a shank including an apertured part for receiving said pin and extending substantially the full vertical depth of the pocket between said bearings, and a closure plate for the pocket opening having a horizontal flange supported from said pocket outwardly from said shank part.

4. In combination, a locomotive pilot having a pocket with a forwardly opening end and with vertically spaced upper and lower walls apertured to form pin bearings, there being an upright pin seated in said bearings, a coupler device having a head at one end and a sleeve at its other end surrounding said pin and extending substantially the full vertical depth of the pocket between the opposing ends of said bearings, and a plate associated with said device and having a part fitting around a portion of said sleeve to pivotally assemble the plate and device so that they are movable about a common axis to a position in which said head is received in said pocket and the open end of said pocket is closed by said plate and to a position in which said plate is received in said pocket and said head is projected forwardly of said pocket.

5. In combination, a locomotive pilot having a pocket with a forwardly opening end and with vertically spaced upper and lower wall members, a coupler device with a head at one end and with its other end extending substantially the full vertical depth of the pocket between said members, a plate associated with said device and adapted to close said pocket open end, and means pivoting the plate and the device about a common axis at the latter-mentioned end of the device so that the plate and the device head may be moved alternately into and out of the pocket.

6. In a locomotive pilot structure, a pilot having a coupler pocket, a coupler pivot pin mounted on said pilot, a laterally swinging coupler pivoted

on said pin and movable into and out of said pocket to non-functioning and functioning positions and comprising a coupler head and a coupler shank, and a pocket closure plate movable with said coupler to close said pocket, said coupler and said closure plate having a common axis, said closure plate pivoting with and on said coupler independently of said pivot pin.

5 7. A closure plate for a locomotive pilot pocket having one end of a coupler device pivotally mounted therein, the plate being provided with a part arranged to fit around and pivot the plate on the pivoted end of the coupler device.

15 8. A closure plate for a locomotive pilot having a pin for pivotally mounting one end of a coupler device, the plate being provided with a circular part fitting around and pivoting on the pinned end of the coupler device.

15 9. A closure plate as described in claim 7 which 20 includes a member arranged to straddle the coupler device with the side elements of said member diverging from the pivoted part to permit the coupler head to swing laterally in operative position to accommodate the vehicle on curves but which will engage the sides of the coupler device 25 to move with the coupler device when the coupler device is moved from an operative to inoperative position or vice versa and thereby move the closure plate to close and uncover the opening in the pilot.

30 10. A closure plate as described in claim 7 in which the pivoted part is provided with an extension to be supported by said pilot and to support the coupler device at a point spaced from its pivoted end.

35 11. A closure plate as described in claim 7 which is constructed and arranged to be supported on the bottom of the pocket independently of the support of the coupler device.

40 12. A closure plate as described in claim 7 which is provided with portions at a lower level than the pivoted portion for supporting the closure plate on the bottom of the pocket independently of the support of the coupler device.

45 13. A locomotive pilot laterally swinging coupler device adapted to be associated with a closure plate for a pilot pocket and comprising a head and a shank, the end of the shank opposite to the head being arranged to surround a pivot pin seated in portions of top and bottom of the pocket and being provided with a circular boss for pivotally mounting the pocket closure plate independently of the pivot pin.

50 14. A coupler as described in claim 13 in which the pivot pin surrounding end of the shank is adapted to extend substantially the full distance between the top and bottom portions of the pocket which seat the coupler pivot pin.
